UNITED STATES PATENT OFFICE.

CHARLES T. DAVIS, OF BROOKLYN, NEW YORK.

DESIGN FOR A METAL WASHSTAND.

No. 38,797.

Specification for Design.

Patented Sept. 10, 1907.

Application filed July 3, 1907. Serial No. 382,114. Term of patent 3½ years.

To all whom it may concern:

Be it known that I, CHARLES T. DAVIS, a citizen of the United States, residing at Brooklyn, in the county of Kings and State of New York, have invented a new, original, and ornamental Design for Metal Washstands, of which the following is a specification, reference being had to the accompanying drawing, forming part thereof.

The figure is a perspective view, showing my new design for metal washstands.

I claim:

The ornamental design for a metal washstand, as shown.

CHARLES T. DAVIS.

Witnesses:

H. R. DAVIS,
HERBERT L. DAVIS.
